UNITED STATES PATENT OFFICE.

CHARLES R. DENNISON, OF YOUNGSTOWN, OHIO.

PLACER-MINING MACHINE.

1,166,192.

Specification of Letters Patent. Patented Dec. 28, 1915.

Application filed July 2, 1913. Serial No. 777,110.

To all whom it may concern:

Be it known that I, CHARLES R. DENNISON, a citizen of the United States, residing at Youngstown, in the county of Mahoning and State of Ohio, have invented certain new and useful Improvements in Placer-Mining Machines, of which the following is a specification.

My invention relates to machines for use in placer mining and its object resides in the provision of a transportable self-propelled apparatus comprising an association of elements which coöperate to effect a rapid and clean separation of the valuable minerals from the worthless matter in metalliferous material delivered to the machine from a placer mine or other deposit.

An embodiment of my invention has been shown in the accompanying drawings in the various views of which like parts are similarly designated and in which,

Figures 1^A and 1^B represent conjointly a side elevation of the machine, and in which Fig. 2, represents a horizontal section taken 25 along the line 2—2, Figs. 1^A and 1^B, Fig. 3, an enlarged transverse section along the line 3—3, Fig. 1^A, Fig. 4, an enlarged fragmentary section taken along the line 4—4, Fig. 2, and Fig. 5, an enlarged section taken along 30 the line 5—5, Fig. 1^A, looking in the direction of the arrow drawn across said line.

Referring to the drawings by numerical reference characters the numeral 2 designates a self-propelled, wheeled carrier upon which the various elements of the apparatus are assembled in coöperative relation to each other.

The metalliferous material obtained from the mine by means of a dredge, steam-shovel or other suitable contrivance is delivered 10 onto a vibrating grizzly 3 at the front end of the carrier, which separates rocks and other coarse matter from the value-bearing finer particles of the material. The coarse matter which remains on the grizzly is conveyed to a dump remote from the machine by means of an endless belt conveyer 4 which is partially shown in Fig. 5 of the drawings, and the finer material is, through 15 the medium of an elevator 5, carried into a rotary washer 6 in which the clayey parts of the material are disintegrated and the valuable mineral-bearing particles are loosened from the stone and gravel with which they 20 are connected. A cylindrical screen 7 formed integral with the washer at the discharge end

thereof, receives the material after it has passed through the washer and effects a cleaner separation of the values and the worthless matter contained therein. The 50 tailings which are discharged through the open end of the screen, fall onto an endless belt 8 which carries them into a bin 9 at the rear end of the machine from which they are subsequently removed to a dump remote 55 from the carrier, by means of an endless belt 10 which is operatively mounted on an adjustable boom 12 which projects outwardly from the rear end of the machine. The valuable matter which is sifted through 60 the meshes of the revolving screen falls onto the upper one of a series of reversely inclined sluice boxes 13 through which it flows from one end to the other, while being concentrated. The lowermost sluice-box dis- 65 charges its contents onto a grizzly 14 through which the concentrates are discharged onto an inclined rifled surface 15 disposed in a compartment 16 of a longitudinally partitioned tank 17, the other compartment 18 70 of which contains an amalgamator 19 into which the material discharged from the said surface is delivered, and in which the metallic parts are extracted from the remaining 75 worthless matter by amalgamation. The 80 amalgam formed in the last mentioned element of my machine is delivered into a retort 20 which is preferably heated by means of the exhaust gases from the engine provided to operate the apparatus, and in which 85 the gold is separated from the mercury with which it is combined, by volatilization of the latter, the vapors being subsequently returned to the amalgamator. The tailings 90 from the amalgamator as well as those dis- 95 charged from the grizzly at the end of the lowermost sluice box are by means of an endless bucket-chain 22 carried into the same bin 9 in which the tailings from the revolving screen are deposited and from 100 which they are removed to the dump by means of the before-mentioned, outwardly projecting conveyer 10 at the rear end of the machine. The water required in the continuous treatment of the material as above 105 described is, by means of a pump, obtained from a suitable source and delivered inside the revolving washer and screen through a perforated pipe 23, and after it has performed its function in the operation of the 110 apparatus, it is by means of a pump 24, drawn out of the tank in which the amalgam-

mator is disposed and into a stack 25 which at its upper end connects with the upper one of the sluice boxes 13. By thus using the same water repeatedly, the machine can be 5 operated at places where the supply of water is limited as only a small quantity is required to replace that lost in the operation. An engine 21 preferably of the internal combustion type, is mounted on the carrier in 10 driving connection with the various elements, and a transmission mechanism of suitable construction is provided for the purpose of transmitting the movement of the engine to one of the axles of the carrier 15 when it is desired to transport the apparatus from one place to another.

Having thus briefly explained the operative relation of the various elements comprised in my invention, I will now proceed 20 to describe the same in detail. I desire it understood, however, that I do not limit myself to the use of the exact constructions shown in the drawings, it being obvious that many variations in the design and arrangement 25 of the various parts comprised in the apparatus can be made without in any way departing from the spirit of my invention and without lessening its efficiency for the rapid and complete separation of the values 30 from extraneous matter in metalliferous ores and sands.

The carrier 2 is composed of a supporting frame 26 made of structural iron and mounted upon two trucks 27. A superstructure 35 28 rigidly mounted on the frame 26 on uprights 29 is provided to support the elevated parts of the apparatus, such as the revolving washer and screen and a line shaft 30 is mounted on the superstructure 40 to transmit the movement of the engine to the various operative parts.

Inasmuch as the arrangement of belts, chains, gears and other transmission devices 45 used for the coöperative connection of the movable parts of the mechanism with the engine, is obvious and plainly shown in the drawings, no detailed description of the same is thought necessary, it being understood 50 that all the parts are adapted for simultaneous operation by either direct or indirect connection with the driving shaft of the engine.

The grizzly 3 at the front end of the machine is surmounted by a hopper 31 into 55 which the material is delivered by the steam-shovel or other contrivance used for excavating the metalliferous deposit.

The grizzly consists of an inclined trough 60 provided as usual with a grating through which the fine matter falls onto the slanting bottom of a subjacent pit 32 from which it is removed by the endless bucket conveyer 5 which elevates it to the washer 6. The rocks and other coarse parts which 65 remained on the grating of the grizzly, fall

over the lower end of the same onto the endless belt 4 which extends laterally from the machine to discharge its load onto a remote dump.

The inclined grizzly is, as best shown in 70 Fig. 5 of the drawings, mounted for vibration upon a roller 33 disposed beneath its lower surface at its lower end, and a rocker arm 34 which supports its opposite end. The rocker arm is oscillated by an eccentric 75 35 which receives its rotary motion from a shaft 36 which by means of a chain 37 is operatively connected with a shaft 38 which is driven by connection with the before-mentioned line shaft.

The rocker arm 34 at one side of the grizzly and the roller, the end of the endless belt conveyer 4 and the eccentric shaft 36 at the opposite side of the same are 80 mounted on brackets 39 and 40 which are 85 bolted to the adjacent uprights 29 of the superstructure of the carrier, and it will be observed that by reversing the position of these brackets, the parts may be readily adjusted to dump the worthless matter discharged over the grizzly, at the opposite 90 side of the machine.

The washer 6 consists of a conoidal drum which is attached at the end of the cylindrical screen 7 in axial alinement therewith, 95 its interior surface may be provided with any suitable means such as the bars indicated at 41 in Fig. 1^A, for disintegrating the material, and an agitating device shown in broken lines at 42 in the same figure, is 100 mounted inside the screen for the usual purpose.

In the operation of the apparatus the connected washer and screen rotate about their alined, longitudinal axes and they are 105 slightly inclined toward the discharge end of the screen which is provided with an outwardly flaring flange 43 to direct the tailings onto the inclined endless belt 8 which conveys them into the bin 9 at the front end of the carrier.

The sluice boxes 13 are reversely inclined and connected at their ends so that the material discharged over the lower end of one will fall into the upper portion of the immediately subjacent one. The lower-most riffle box is at its discharge end connected with the grizzly 14 which is disposed above the upper portion of the inclined, riffled sluice box 15 in the tank 17.

The upper two sluice boxes are secured between the adjacent uprights 29 of the superstructure by means of bolts or other detachable devices which permit of changing the angles of inclination of the boxes in accordance with the character of the material under treatment.

The grizzly 14 which connects with the lower box 13 is movably mounted upon suitable supports and a pair of cams 68 on a 120

5 rotary shaft 59 engages the lower surface of the grizzly for the purpose of imparting a vibratory motion thereto. The shaft 59 is by means of a sprocket-chain 70 connected with a counter-shaft 71 which receives its rotary movement from the shaft 30.

10 The sluice box 15 is disposed at one side of the longitudinal partition 44 which divides the tank into two compartments, and its lower end is spaced from the adjacent end of the tank to discharge the matter flowing over the same into the bottom portion of the tank whence it flows through an opening 45 in the partition into the amalgamator 15 which is mounted in the compartment at the opposite side of the same.

20 While the amalgamator shown in elevation in the drawings, may be of any suitable construction, I preferably employ an apparatus composed of a cylinder in which a rotary device is mounted to convey the material fed into one of its ends, to its opposite end at which it is discharged into the compartment in which it is disposed.

25 The cylinder is by means of pipes 48 connected with the retort 20 and which is heated by the exhaust gases of the engine conveyed thereto through a conduit 47.

30 The mercury vapors generated in the retort are returned to the amalgamator by means of pipes 46. The tailings discharged from the amalgamator cylinder are by means of a suction-wheel 49 shown in Figs. 2 and 4 of the drawings, drawn into a flue 50 which at 51 has an over-flow in communication with the rearmost portion of the tank from which the tailings are by means of the inclined endless bucket chain 22, removed to the bin 9 into which the matter 40 discharged from the rotary screen is likewise deposited.

45 The buckets of the conveyer 22 are perforated as shown in Fig. 4, for the purpose of draining the water from the tailings into the end of the tank from where it flows through the space around the lower portion of the amalgamator cylinder and through the space beneath the riffle-box, to the forward end of the tank, whence it is drawn by the action of the pump 24 and discharged into the stack 25 which at its upper end connects with the uppermost riffle-box.

50 The perforated pipe 23 through which the water is supplied inside the washer and the screen, may be connected by any suitable means at the lower end of a vertical conduit 52, with a source of supply from which the water can be drawn either by the pump on the carrier or by a separate suction-pump.

60 The bin 9 discharges the tailings onto the endless belt conveyer 10 which as hereinbefore described is mounted on a boom 12 which extends outwardly from the machine

to dump its load at a point remote therefrom. The boom which is made of structural iron, is pivotally mounted at its lower extremity in bearings 53 on the rear end of the carrier, and it is at its front end, suspended by means of a tackle 54 from a winding drum 55 which is mounted on the superstructure 28.

70 The drum which is normally held against rotation by a pawl and ratchet or other suitable device, is by means of gear wheels 56 and 57 operatively connected with a shaft 58 which may be rotated by the application of a hand-crank to its squared extremity for the purpose of varying the angle of inclination of the boom.

75 The endless conveyer mounted on the boom, runs at its lower end around a drum 59 which by means of a chain 60 receives its rotary motion from a counter-shaft 61 which through the medium of a sprocket chain 62 is connected with a second counter-shaft 63 which receives its movement directly from the engine by means of a belt 64.

80 In the construction shown in Fig 1^B of the drawings the boom is positioned so as to dump its load at a point rearward of the machine, but as it may be more desirable to deposit the tailings at points at either side of the machine, I have provided at the extreme end of the carrier two right-angled 90 angularly mounted shafts which are operatively connected by means of beveled gears 65. One of these shafts has a sprocket wheel which by means of a chain 66 may be connected with the before-mentioned counter-shaft 61 and the other shaft which is designated in the drawings by the numeral 168, is adapted for the attachment of the conveyer drum at the lower end of the boom when the latter together with the bearings 95 on which it is mounted, is moved into operative relation to said shaft.

95 A suitable transmission mechanism designated by the reference character 67 in Fig. 1^A is disposed between a driving wheel 110 on the engine 21 and a driven wheel on one of the axles of the front truck of the carrier for the purpose of propelling the machine to or from the point at which it is desired to operate.

115 I claim—

1. A machine of the type described, including co-operative elements for the extraction of metal from metalliferous material, comprising an amalgamator and a retort 120 connected therewith to receive the amalgam discharged therefrom and adapted to recover the amalgam by vaporization, an engine in driving connection with said elements, and means for conducting the exhaust from said engine to said retort to heat the contents thereof.

125 2. A machine of the type described, in-

- cluding coöperative elements for the extraction of metal from metalliferous material comprising an amalgamator and a retort connected therewith to receive the amalgam discharged therefrom and adapted to recover the amalgam by vaporization, a receptacle within which is arranged said amalgamator, for receiving said metalliferous material for feeding to said amalgamator, means for the treatment of said material preliminary to delivery into said receptacle and feeding to said amalgamator, said amalgamator being adapted to receive said material from said receptacle, suction means arranged in said amalgamator to take the material therefrom after treatment therein, heat-operated means, in driving connection with said elements, adapted to deliver a high temperature exhaust.
3. A machine of the type described, including coöperative elements for the extraction of metal from metalliferous material, comprising an amalgamator, a retort connected therewith to receive the amalgam discharged therefrom and arranged to recover the amalgam by vaporization, heat-actuated means in driving connection with said amalgamator, and means for conducting the exhaust from said heat actuated means to said retort to heat the contents thereof.
4. A machine of the type described, including coöperative elements for the extraction of metal from metalliferous material, comprising an amalgamator, a retort connected therewith to receive the amalgam discharged therefrom and arranged to recover the amalgam by vaporization, suction means arranged in said amalgamator to remove the contents thereof, driving means in connection with said amalgamator and including an internal combustion

engine, and means for conducting the exhaust from said driving means to said retort to heat the contents thereof.

45

5. A machine of the type described, including coöperative elements for the extraction of metal from metalliferous material, comprising an amalgamator having an upstanding cylinder, with a suction or exhaust producing member arranged therein for effecting the removal of the contents of said amalgamator, a retort connected to said amalgamator to receive the amalgam discharged therefrom and adapted to recover the amalgam by vaporization, an engine in driving connection with said elements and means for conducting the exhaust from said engine to said retort to heat the contents thereof.

60

6. A machine of the type described, including coöperative elements for extracting metal from metalliferous material, comprising means for amalgamating said material, a retort in communication therewith to receive the amalgam discharged from said amalgamator and arranged to recover the amalgam by vaporization, a heat-actuated driving means in connection with said amalgamator, means for conducting the exhaust from said heat-actuated driving means to said retort to heat the contents thereof, means for treating the material preliminary to being fed to said amalgamator, including separating means, washing means, screening means and means for subjecting the material to a sluicing action.

75

In testimony whereof I have affixed my signature in presence of two witnesses.

CHARLES R. DENNISON.
